(57) **CLAIM**

The ornamental design for combined interdental brush holder with brush and cap, as shown and described.

DESCRIPTION

FIG. 1 is a front elevational view of the brush holder portion of the combined interdental brush holder with brush and cap embodying our new design;

FIG. 2 is a left side elevational view thereof;

FIG. 3 is a rear elevational view thereof;

FIG. 4 is a left side elevational view thereof shown in combination with a detached brush;

FIG. 5 is a left side elevational view thereof shown with a brush attached;

FIG. 6 is a left side elevational view thereof shown in combination with an attached cap;

FIG. 7 is a left side elevational view thereof shown in combination with the cap when detached;

FIG. 8 is a front elevational view of the cap of the combined interdental brush holder with brush and cap;

FIG. 9 is a left side elevational view thereof; and,

FIG. 10 is a rear elevational view thereof.

The phantom line showing in the figures is for illustrative purposes only and forms no part of the claimed design.

The top and bottom surfaces or portions of the article neither shown in the drawings nor described in the specification form no part of the claimed design.

The brush holder and cap are shown separately for clarity or ease of illustration.
